UNITED STATES PATENT OFFICE.

JAMES J. WEAVER, OF GALVESTON, TEXAS.

HINGE CONSTRUCTION.

1,269,764.

Specification of Letters Patent. Patented June 18, 1918.

Application filed August 22, 1917. Serial No. 187,723.

To all whom it may concern:

Be it known that I, JAMES J. WEAVER, a citizen of the United States, residing at Galveston, in the county of Galveston and 5 State of Texas, have invented certain new and useful Improvements in Hinge Construction, of which the following is a specification.

The invention has for an object to provide a hinge which may be readily manufactured, having means to hold the leaves yieldably at various points of their relative movement, whereby doors hung by the use of the hinge will not tend to slam or move 10 casually into closed position. It is a particular object to provide an improved method of constructing the elements by which the leaves are held against casual movement. It is a particular object to give 15 a method for forming the hinge complete, in two pieces, thereby minimizing expense in assembly during manufacture as well as expenditure of time in installation, and eliminating liability of loss of parts and 20 liability of improper ordering of the elements.

Additional objects, advantages and features of invention will appear from the construction, arrangement, and combination of 30 parts hereinafter described and shown in the drawings, wherein;

Figure 1 is a top view of the hinge in open position,

Fig. 2 is an elevational view of the hinge 35 in the same position before mentioned,

Fig. 3 is a plan of the blank for one of the leaves,

Fig. 4 is a similar view of the blank for the other leaf,

Fig. 5 is an edge view of the complete 40 hinge, in closed position.

Fig. 6 is a reduced elevation of the hinge as used on the bottom of a door.

There is illustrated a portion 10 of the 45 rear end of a vehicle including the side piece 11 of a door frame, upon which a door 12 of any usual construction is hung, by means of hinges constructed in accordance with my invention. The hinge includes a 50 leaf 13 which may be termed the anchor leaf, and the leaf 14 coöperating therewith which may be termed the swinging leaf, although the last mentioned leaf may be secured to a supporting frame and the first mentioned 55 leaf used as the swinging part, if desired. The leaf 13 comprises a body portion sub-

stantially rectangular in form, and which may be stamped from sheet metal by familiar methods, the usual knuckles 15 being formed upon the inner edge, for coöperation with 60 like knuckles 16 arranged in staggered relation thereto upon the leaf 14, corresponding in form to the first mentioned leaf and also produced by similar methods. While shown in sheet metal, the hinge may also be produced by other methods if desired. 65

The leaf 13 at one end is formed with an integral anchor plate 17, partly circular in form, concentric with the knuckles 14, from which there extends an integral supporting 70 plate 18, forming a part of the leaf 13. In the formation of this leaf, the blank is cut as shown in Fig. 4 the body having a diagonal end edge 19, an arcuate slit 20 being cut in the body adjacent its inner edge, the 75 inner end of the slit being approximately at right angles to a line vertical with the outer edge of the plate, and forming a continuation of a curved corner edge portion 21, of which the end edge 19 forms a tangent. The outer end portion of this blank and the portion included between the slit 20 and rounded edge 21 are then bent into 80 a plane at right angles to the major portion of the blank, on a line terminating at the inner end of the slit 20, and at right angles to the outer longitudinal edge of the blank. At intervals in the curved edge portion 21, notches 22 are formed, for purposes 85 which will be subsequently described. 90

The leaf 14 of the hinge is somewhat simpler in form, and has an integral spring tongue 23 formed thereon, which is pressed laterally from the plane of the blank, its 95 base lying slightly beyond the radius of the arc 20-21, as measured from the knuckles 15, the spring being slightly curved concentrically with the knuckles and having its outer end turned inwardly abruptly and re-curved to form a rounded wiper 24 adapted 100 to engage snugly in the notches 22 alternatively.

It may be noted that the material of the anchor piece 17 and the material of the spring 23 do not extend much beyond the 105 line of the extremities of the ears 15', 16', in the blank, from which the corresponding knuckles of the hinge are formed, so that there is a minimum waste of material in the stamping of the parts for the hinge. 110

If desired, the anchor portion 17 may have a flange 25 formed therearound, in

alinement with its edge portion, which will serve to stiffen the anchor and also to give a greater bearing for the wiper 24 upon the spring. It will be seen that by properly 5 spacing the ears for the knuckles, the spring will be held in such position that the plate 17 will strike intermediately of the width of the spring 23, so that the latter will properly engage the edge of the plate and 10 be held by the notches 22. The flange 25 may be formed integrally upon the plate 17 by blanking the latter out in an adequate size and forming the blank between proper dies adapted to turn up the edge portion of 15 the plate 17 and stretch or pack the metal into the desired form.

The notches 22 may be spaced to hold a door yieldably in any number of different positions, and as illustrated they are located 20 so as to hold the door at an angle of 90 degrees to the plane of the opening which it closes, and in a position in alinement with said plane. When the device is used for doors of buildings, it may be desirable to 25 have the notches more numerous and located at closer intervals.

In the case of the lower hinge on a wagon body, the hinge may be so located upon the frame 11 and the door 12, that the plate 17 lies below the wagon body slightly, and below the door 12, so that no mortising is 30 necessary. In the case of doors for buildings, the plate 17 may be made of such size that a very slight mortise will be required to 35 accommodate the device upon the door and frame.

In practice, it has been found sufficient to make the plate 17 with a diameter of one 40 inch, and it may be made even of smaller diameter and still be efficient for yieldably holding doors of considerable size, especially when the spring tongue is properly formed.

By increasing the width of the tongue its 45 force in holding the door at various positions will of course be materially increased, and this strength will also be greater where

thick sheet material is used for producing the spring.

The usual pintle 26 is engaged commonly 50 through the knuckles 15 and 16.

It will be seen that an extremely simple hinge construction is provided for attaining the objects in view.

What is claimed:

1. A hinge comprising a leaf having a partly circular portion formed at the inner part of the leaf, and having an extension therefrom across the end of the leaf, said partly circular portion and extension being 60 bent into a plane at right angles to the leaf, a second leaf having a spring tongue formed thereon positioned to bear upon the edge portion of said partly circular portion of the first mentioned leaf, intermeshed knuckles formed on the leaves, a pintle therein, said partly circular portion being notched for the purpose described.

2. As an improved article of manufacture, 70 a hinge comprising a blank having knuckle ears formed upon one edge, and having a diagonal end edge and partly circular inner corner edge thereadjacent, an arcuate slit being formed in the inner edge portion of the blank concentric with said semi-circular 75 edge, the end portion of the blank outwardly of said slit, including a part extending toward the outer edge of the blank from said slit, being bent into a plane at right angles to the major portion of the blank, and a second leaf having knuckle ears in staggered 80 relation with those first mentioned and a transverse slit extending from the inner edge of the blank, the material outwardly of said slit being bent laterally and shaped to form 85 a spring and wiper for engagement with the circular edge portion of the first mentioned member when assembled.

In testimony whereof I have affixed my signature in presence of two witnesses.

JAMES J. WEAVER.
